UNITED STATES PATENT OFFICE

JOSEPH F. FRADLEY, OF BROOKLYN, NEW YORK.

DESIGN FOR A BRUSH-BACK, &c.

SPECIFICATION forming part of Design No. 24,379, dated June 11, 1895.

Application filed February 13, 1895. Serial No. 538,292. Term of patent 3½ years.

To all whom it may concern:

Be it known that I, JOSEPH F. FRADLEY, of the city of Brooklyn, county of Kings, and State of New York, have invented and produced a new and original design for a Brush-Back or Similar Article, of which the following is a specification.

I will describe a brush back in detail, embodying my design and then point out the novelty in a claim.

The accompanying drawing is a back view of a hair-brush embodying my design.

The general outline of the brush back, A, is of oval form. Along the edge is a scalloped ornamental border a , having alternately raised and depressed portions a' , a'' ; the raised portions extending farther from the edge of the brush back than the others. At intervals, foliate ornaments a^3 extend inwardly from

the border a . At each end of the brush back, 20 I have shown an oval figure, a^4 , and extending therefrom, a foliate ornament a^5 . In the center of the brush back is a medallion a^6 , with a foliate marginal portion a^7 . The body or main portion of the brush back is ornamented with longitudinal ribs a^8 .

What I claim as my design, and desire to secure by Letters Patent, is—

The design for a brush back, or similar article, substantially as described and shown. 30

In testimony whereof I have signed my name to this specification in the presence of two subscribing witnesses.

JOSEPH F. FRADLEY.
